FENCE PANEL AND POSTS UNIT

Robert Grubbs, Boron, Calif.

Application June 2, 1958, Serial No. 51,160

Term of patent 14 years

(Cl. D28—1)

Fig. 3 is a longitudinal sectional view on line 3—3 of Fig. 1.

The opposite side of the fence panel and posts unit is identical with that shown in Fig. 1.

I claim:

The ornamental design for a fence panel and posts unit, substantially as shown and described.
